[57] CLAIM

The ornamental design for a building with solar concentrator roof, as shown and described.

DESCRIPTION

FIG. 1 is a perspective view of building with solar concentrator roof showing the new design.

FIG. 2 is a fragmentary top plan view thereof.

FIG. 3 is a fragmentary side elevational view thereof.

FIG. 4 is a fragmentary perspective view of an alternative embodiment of the building with solar concentrator roof as seen in FIG. 1 except for a scalloped type roof panel.

FIG. 5 is a fragmentary perspective view of another alternative embodiment of the building with solar concentrator roof as seen in FIG. 1 except for the addition of a roof panel.

FIG. 1

FIG. 2

FIG. 3

FIG. 4

FIG. 5
